[57] CLAIM

The ornamental design for a head ornament, substantially as shown and described.

DESCRIPTION

FIG. 1 is a front elevational view of a head ornament showing my new design;

FIG. 2 is a side elevational view thereof; the broken line showing of a human head is for illustrative purposes only;

FIG. 3 is a top plan view thereof;

FIG. 4 is a top plan view of another embodiment of the head ornament shown in FIG. 1;

FIG. 5 is a front elevational view thereof; and

FIG. 6 is a side elevational view thereof.

FIG.1.

FIG.2.

FIG.3.

FIG.4.

FIG. 5.

FIG. 6.
